[57] CLAIM

The ornamental design for a sling-supported drawing board or similar article, substantially as shown and described.

DESCRIPTION

FIG. 1 is a side elevational view of the sling-supported drawing board or similar article showing my new design.

FIG. 2 is another side elevational view thereof, showing the side opposite to that illustrated in FIG. 1.

FIG. 3 is a top plan view thereof.

FIG. 4 is a bottom plan view thereof.

FIG. 5 is a rear elevational view thereof.

FIG. 6 is a front elevational view thereof.
